(57) **CLAIM**

The ornamental design for a mouse for a computer, as shown and described.

DESCRIPTION

FIG. 1 is a front view of a mouse for a computer;
FIG. 2 is a rear view thereof;
FIG. 3 is a right-side view thereof;
FIG. 4 is a left-side view thereof;
FIG. 5 is a top view thereof;
FIG. 6 is a bottom view thereof;
FIG. 7 is a perspective view thereof; and,
FIG. 8 is a perspective view of FIG. 7 illustrating a portion of a connection cable to a computer.

The broken line showing is for illustrative purposes only, and does not form part of the claimed design.
